US0D1113975S

(12) **United States Design Patent** (10) Patent No.: **US D1,113,975 S**
(45) Date of Patent: ** Feb. 17, 2026

(54) **DISPLAY SCREEN OR PORTION THEREOF
WITH ICON**

(71) Applicant: **Samsung Electronics Co., Ltd.**,
Gyeonggi-do (KR)

(72) Inventors: **Tengwen Hu**, Newark, CA (US); **Joo
Hyun Bae**, San Jose, CA (US)

(73) Assignee: **SAMSUNG ELECTRONICS CO.,
LTD.**, Gyeonggi-Do (KR)

(**) Term: **15 Years**

(21) Appl. No.: **30/014,957**

(22) Filed: **Jul. 25, 2025**

Related U.S. Application Data

(60) Continuation of application No. 29/880,569, filed on Jul. 25, 2023, now Pat. No. Des. 1,090,623, which is a division of application No. 29/737,506, filed on Jun. 9, 2020, now Pat. No. Des. 997,196.

CLAIM

The ornamental design for display screen or portion thereof with icon, as shown and described.

DESCRIPTION

THE FIGURE is a front view of a display screen or portion thereof with icon, showing our new design.

The outermost broken lines showing the display screen or portion thereof in the FIGURE form no part of the claimed design. The remaining broken lines show portions of the icon and form no part of the claimed design.
